(57) **CLAIM**

The ornamental design for sound muffling headwear, as shown and described.

DESCRIPTION

FIG. 1 is a left side perspective view of a sound muffling headwear showing our new design;

FIG. 2 is a right side perspective view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a rear elevation view thereof;

FIG. 8 is a front elevation view thereof; and,

FIG. 9 is another perspective view thereof, shown in a used condition attached to headwear, which is shown in broken lines representing the environment of the invention and forms no part of the claimed design.
